UNITED STATES PATENT OFFICE

FRED HARRISON, OF WORCESTER, ENGLAND.

DYNAMOMETER.

1,035,700.

Specification of Letters Patent. Patented Aug. 13, 1912.

Application filed March 11, 1912. Serial No. 683,946.

To all whom it may concern:

Be it known that I, FRED HARRISON, a British subject, residing at Worcester, county of Worcester, England, have invented certain new and useful Improvements in Dynamometers, of which the following is a specification.

This invention relates to improvements in the valve gear for rotary absorption dynamometers in which a turbine or rotor revolves within a casing suitably mounted on friction rollers and connected to a water supply to enable the casing to run full of water when the machine is in use.

15 It has been proposed to connect the inlet and outlet valve levers by links and to operate them simultaneously by a screw the movement of which is very slow.

This invention is designed to provide a 20 valve gear whereby the dynamometer may be employed for indicating horse powers considerably above or below its normal range on occasions when the prime mover is subjected suddenly to large overloads or 25 underloads.

It consists in the arrangement of links and levers by which the inlet and outlet valves are operated by a single lever which can be quickly moved a considerable distance the 30 movement of which in one direction causes the inlet valve to be further opened and outlet valve closed and its movement in the reverse direction causes the inlet valve to be closed and outlet valve further opened.

35 The invention will be fully described with reference to the accompanying drawings forming part of the specification.

Figure 1 is a side elevation of a rotary absorption dynamometer with the invention 40 applied thereto. Fig. 2 is a front elevation of same.

A lever *m* is mounted on the inlet valve *M* on the inlet pipe *F* and a quadrant shaped lever *n* is mounted on the outlet valve *N* 45 and both these levers *n* and *m* are pivotally connected at the ends to a connecting link *O*. A spindle *p* extending across the dynamometer is carried by two brackets *P* and *P'* affixed to the bed plate of the dynamometer.

50 An operating lever *R* is affixed to one end of the spindle *p* and moves over a quadrant bracket *S* carried on the frame of the machine. This quadrant bracket *S* is provided with a slot *s* in which a spring clip *r* on 55 the operative lever *R* slides on any move-

ment of this lever so that when the lever is moved to the desired position it will be held there. The lever *n* affixed to the outlet valve *N* is connected to the spindle *p* by the link *O'* and the lever *O²* mounted on the spindle *p*. The link *O'* and the lever *O²* are pivotally connected so that they can turn about each other. The end *o'* of the link *O'* attached to the lever *n* is pivotally mounted on a threaded rod *n'* carried by this lever *n* so that its distance from the spindle of the outlet valve *N* can be varied. A weight *T* is attached by the arms *t* and *t'* to the stator on the opposite side of the dynamometer to that on which the balance arm *E* and weight *W* are placed and the weight *T* is arranged to balance the spring balances *V* and *V'* for measuring the under and over load and the sliding weight *v* when the latter is in the zero position on the 75 arm *v'*.

When the operating lever *R* is held in its central position on the quadrant *S* (as shown in Fig. 1) the valves *M* and *N* are arranged to open and close normally so that if the machine is being used for a test it records in the usual way the power absorbed thereby. When it is desired to put on an overload the operating lever *R* is moved upward toward the end *s'* of the quadrant *S*. This movement of the lever *R* rotates the spindle *p* and with it the lever *O²* causing the link *O'* lever *n*, link *O* and lever *m* all to be moved. The movement of the lever *n* causes the outlet valve *N* to be closed and that of the lever *m* causes the inlet valve *M* to be opened, the amount of their respective closing and opening depending upon the extent of the movement of the operating lever *R*. When on the other hand it is desired to reduce the load *i. e.*, put on an underload the operating lever *R* is moved downward toward the end *s²* of the quadrant *S*. This causes the shaft *p* to be rotated in the opposite direction so that the lever *n* and lever *m* are also moved in the opposite direction and consequently the inlet valve *M* is closed, and the outlet valve *N* is opened. The amount of their respective closing and opening depends upon the extent of the movement of the operating lever *R*. The amount of the overload is measured on the overload spring balance *V* and of the underload on the underload spring balance *V'* operated by the arm *E*.

What I claim as my invention and desire to protect by Letters Patent is:—

1. In a rotary absorption dynamometer, the combination, with a casing having fluid inlet and outlet pipes communicating therewith, and a valve associated with each of said pipes; of an actuating lever connected to each valve; a link connection between said levers; a spindle; a link connection between one of said levers and said spindle; and means for operating said spindle whereby said valves may be suddenly opened or closed when the dynamometer is employed for indicating powers considerably above or below its normal range.

2. In a rotary absorption dynamometer, the combination, with a casing having fluid inlet and outlet pipes communicating therewith, and a valve associated with each of said pipes; of an actuating lever connected to each valve; a link connection between said levers; a spindle; a link connection between one of said levers and said spindle; a slotted quadrant bracket associated with said spindle; and a hand lever affixed to said spindle for operating the same, whereby said valves may be suddenly opened or closed when the dynamometer is employed for indicating powers considerably above or below its normal range, said hand lever being movable across said bracket and provided with a retaining device operative in the slot therein.

3. In a rotary absorption dynamometer, the combination, with a casing having fluid inlet and outlet pipes communicating therewith, and a valve associated with each of said pipes; of an actuating lever connected to each valve; a link connection between said levers; a spindle; a threaded rod adjustably carried by one of said levers; a link connection between said rod and said spindle; and means for operating said spindle, whereby said valves may be suddenly opened or closed when the dynamometer is employed for indicating powers considerably above or below its normal range.

4. In a rotary absorption dynamometer, the combination, with a casing having fluid inlet and outlet pipes communicating therewith, and a valve associated with each of said pipes; of an actuating lever connected to each valve; a link connection between said levers; a spindle; a threaded rod adjustably carried by one of said levers; a link connection between said rod and said spindle; a slotted quadrant bracket associated with said spindle; and a hand lever affixed to said spindle for operating the same, whereby said valves may be suddenly opened or closed when the dynamometer is employed for indicating powers considerably above or below its normal range.

5. In a rotary absorption dynamometer, the combination, with a casing having fluid inlet and outlet pipes communicating therewith, and a valve associated with each of said pipes; of an actuating lever connected to each valve; a link pivotally connected at opposite ends to said levers; a spindle; a lever secured thereto; a link pivotally connected at opposite ends to the second-named lever and one of the first-named levers; and means for operating said spindle, whereby said valves may be suddenly opened or closed when the dynamometer is employed for indicating powers considerably above or below its normal range.

6. In a rotary absorption dynamometer, the combination, with a casing having fluid inlet and outlet pipes communicating therewith, and a valve associated with each of said pipes; of an actuating lever connected to each valve; a link pivotally connected at opposite ends to said levers; a threaded rod adjustably carried by one of said levers; a spindle; a lever secured thereto; a link pivotally connected at opposite ends to said rod and the second-named lever; and means for operating said spindle, whereby said valves may be suddenly opened or closed when the dynamometer is employed for indicating powers considerably above or below its normal range.

7. In a rotary absorption dynamometer, the combination, with a casing having fluid inlet and outlet pipes communicating therewith, and a valve associated with each of said pipes; of an actuating lever connected to each valve; a link pivotally connected at opposite ends to said levers; a threaded rod adjustably carried by one of said levers; a spindle; a lever secured thereto; a link pivotally connected at opposite ends to said rod and the second-named lever; a slotted quadrant bracket associated with said spindle; and a hand lever affixed to said spindle for operating the same, whereby said valves may be suddenly opened or closed when the dynamometer is employed for indicating powers considerably above or below its normal range.

8. In a rotary absorption dynamometer, the combination, with a casing having fluid inlet and outlet pipes communicating therewith, and a valve associated with each of said pipes; of an actuating lever connected to each valve; a link pivotally connected at opposite ends to said levers; a threaded rod adjustably carried by one of said levers; a spindle; a lever secured thereto; a link pivotally connected at opposite ends to said rod and the second-named lever; a slotted quadrant bracket associated with said spindle; and a hand lever affixed to said spindle for operating the same, whereby said valves may be suddenly opened or closed when the dynamometer is employed for indicating powers considerably above or below its normal range, said hand lever being movable across said bracket and provided with a retaining device operative in the slot therein.

In testimony whereof I have hereunto set my hand in presence of two subscribing witnesses.

FRED HARRISON.
